DESIGN FOR A SQUARING DEVICE FOR KNOCK - DOWN CLOTHES DRYING FRAMES

Dannie Jay Butts, Alhambra, Calif.

Application March 5, 1940, Serial No. 90,679

Term of patent 14 years

To all whom it may concern:

Be it known that I, Dannie Jay Butts, a citizen of the United States, residing at Alhambra, in the county of Los Angeles and State of California, have invented a new, original, and ornamental Design for a Squaring Device for Knock-down Clothes Drying Frames, of which the following is a specification, reference being had to the accompanying drawing, forming part thereof.

Figure 1 is a top plan view of a squaring device for knock-down clothes drying frames, showing my new design; and

Figure 2 is a cross section on the line 2—2 of Fig. 1.

I claim:

The ornamental design for a squaring device for knock-down clothes drying frames, as shown.

DANNIE JAY BUTTS.
